UNITED STATES PATENT OFFICE

GEORGE GRAHAM CROMARTIE, OF MAPLEWOOD, NEW JERSEY, ASSIGNOR TO BEST
MANUFACTURING COMPANY, OF IRVINGTON, NEW JERSEY, A COPARTNERSHIP

DESIGN FOR A LOUD-SPEAKER

Application filed January 17, 1930. Serial No. 34,165. Term of patent 14 years.

To all whom it may concern:

Be it known that I, GEORGE GRAHAM CROMARTIE, residing at 16 Maple Terrace, Maplewood, county of Essex, State of New Jersey, have invented a new, original, and ornamental Design for a Loud-Speaker, of which the following is a specification, reference being had to the accompanying drawing, forming a part thereof, in which

I claim:

The ornamental design for a loud speaker as shown.

GEORGE GRAHAM CROMARTIE.
